UNITED STATES PATENT OFFICE.

FRANCIS M. WOLFE, OF DURANT, OKLAHOMA.

MUSIC-CHART.

1,177,002.

Specification of Letters Patent. Patented Mar. 28, 1916.

Application filed August 30, 1913. Serial No. 787,538.

To all whom it may concern:

Be it known that I, FRANCIS M. WOLFE, a citizen of the United States of America, residing at Durant, in the county of Bryan and State of Oklahoma, have invented certain new and useful Improvements in Music-Charts, of which the following is a specification.

My invention relates to improvements in music charts, and more particularly to charts adapted for positioning in juxtaposition to the keys of a musical instrument for the purpose of enabling the performer to more readily select the keys to be operated and at the same time enable the theory to be clearly understood.

The objects of my invention are to provide a chart of this type which is simple and readily understood, which will serve as an efficient guide both in performing and understanding the underlying theories, and which is arranged to permit its use in connection with any key signature.

To this and other ends, the nature of which will be readily understood as the invention is hereinafter disclosed, my invention consists in the general arrangement and combination hereinafter more fully described in the accompanying drawings, and more particularly pointed out in the appended claim.

In the accompanying drawings, in which similar reference characters represent similar parts in each of the views: Figure 1 is a plan view of the chart with the slide removed, said chart indicating the key of C. Fig. 2 is a plan view of the chart, the slide being shifted to indicate the scale in the key of G. Fig. 3 is a cross section of Fig. 1. Fig. 4 is an enlarged view of one portion of the device.

The chart comprises a main portion, indicated as an entirety at 20.

21 designates a shiftable member which may be employed to indicate the scale in other keys than C-major, the main chart having its arrangement based solely on such C-major scale.

The charts may be of suitable material, such as pasteboard, or for example, printed sheets mounted upon a base of suitable material, the base being shown in the drawings at 20^a. Furthermore, the member 21 may be secured in position in any suitable way as by fasteners. In the drawings, however, I have shown a more rigid structure in that

the member 21 is in the form of a metallic plate 21^a having side flanges 21^b which are adapted to be inserted in grooves 20^b in the base, this relative arrangement being best shown in Fig. 3.

The main chart 20 is provided with a representation of the keyboard of a piano, said representation being adjacent the bottom, so that by placing the chart on the keyboard of a piano or the like, the different representations on the chart will be properly positioned above the respective keys. This portion of the chart is indicated at 22, and may be of a length to cover all or a major portion of the keyboard. An intermediate portion of this representation is continued upwardly a suitable distance to provide visual indications of the particular piano keys which should be employed in the formation of chords based on the scale of C-major, together with portions on opposite sides of the chord indications (the latter being indicated at 23) which set forth at 23^a, the notes of the major scale, and at 23^b, the notes of the harmonic minor scale. These notes are indicated by numerals positioned within the spaces corresponding to the piano keys which are employed in producing these scales, the three parts 23, 23^a, 23^b being separated by longitudinal lines to segregate the parts from each other. For the purpose of bringing out the various features of the chart, this particular portion preferably extends a distance corresponding to three octaves, "middle C" being substantially the center.

Any suitable indications may be employed for readily showing which keys are to be combined for forming a chord of particular character. Within the space 23 I have shown these indications as being in the form of double-headed arrows, the direction in which the arrows extend indicating the particular chord. For instance, the "tonic" chord is indicated by the horizontal arrow, and wherever this arrow appears within this particular part of the chart, that particular key is properly one of those employed in making this chord. The "dominant" chord is indicated by the vertical arrow, while the "sub-dominant" chord is indicated by the inclined arrows. Where a key is exhibited as having parallel arrows, it shows that that particular key indicates the base of that particular chord, the chords illustrated being those of the major scale.

The vertical lines representing the keys

are continued to the top of the chart for a distance approximately equal to one octave, this being preferably the octave at the left of the scale, and on these extensions are the 5 key representations. On the representation of a staff, indicated at 24, which extends throughout the length of this portion of the chart, I place the key signatures of which the key representations form the tonic bass. 10 For instance, on the representation of the key of F, I locate the key signature of one flat; on the key of G, that of one sharp, etc., the key signatures covering the entire changes within the octave. This particular 15 portion of the staff scale is indicated at 24^a.

On the staff 24 I also place, either in the proper spaces of the part 24^a or at proper locations on the remainder of the chart, heavy indications which show the location 20 of the particular key on the lines and spaces of the staff, thus clearly associating these indications both with the position of the keys on the instrument and also the letters representing these keys, each of these representations or indications being in vertical 25 alinement. These indications appear as notes 24^b.

On the staff portion of the chart and preferably at proper positions thereon corresponding to the position of the bass note 30 of the chord, I indicate in skeleton form the additional members 24^c of a particular chord, showing the location on the staff of these additional members. For instance, the 35 space representing key F carries, on the staff, the note indications of the sub-dominant chord; key G carries that of a dominant chord, while key C carries that of a tonic chord, these being shown at different 40 places on the staff. In addition, I have shown, at 24^d the notes which indicate the minor chord of this particular scale. At the right of the staff, I indicate in letters the particular designation of each line and 45 space.

As will be seen from Fig. 1, the staff 24 is located spaced from the part 23, and I make use of this space to indicate various 50 triads, the different notes which form a particular triad being connected by braces, as indicated at 25, and the ends of the brace and the center indicating the three tones which form the triad. In this way, not only is there provided a visual indication of the 55 manner in which triads are formed, but in addition, the visual indications are presented both with respect to the note representation on the staff, and the location of the keyboard, thus enabling the user to 60 clearly associate the two parts and facilitate sight reading of the music. Within this space I also indicate octaves, tetrachords as well as the minor triads, the relative form of a tetrachord being designated as well as 65 the locations thereof with respect to each

other. By this arrangement, it will be readily understood that all of the knowledge based on theory with respect to the natural scale is contained in the chart, and in such form that the performer will readily 70 associate the various facts both with respect to the staff and to the instrument, the general arrangement being such as to provide the results with facility and in a manner readily understood thereby enabling the beginner 75 in the study of music as well as its theory, to clearly understand the subject and permit of rapid progress being made.

As heretofore pointed out, the main chart pertains particularly to the C-major scale 80 alone. To enable this information to be applied with respect to other scales, I preferably employ the shiftable chart 21, carrying indications which are to take the place of the parts 23 and 25. This particular chart 85 shows a different way in which the chord-members may be indicated, the indications being by color and not by arrows as in the main chart. For instance, the tonic chords are indicated in red, the dominant in blue, 90 and the sub-dominant in black. It will also be seen that the colored portions are of two types, some of them being in the form of squares, and others in the form of oblongs. Where the representation is in the form of a 95 square, the lower portion indicates that this particular key is in the bass of the chord, while the oblongs extending horizontally indicate parts of the chords. It will also be noted that in some cases small oblongs or 100 squares are employed, and these are intended to represent the additional keys which would change the triad into a chord of the "diminished 7th," this assisting materially in modulation.

In use, the scale 21 is placed over the portion of the scale 20 for which it is to be substituted, the bass of the tonic chord, indicated by the large red square, being brought into alinement with the desired key signature in the part 24^a. For instance, if placed in alinement with the key signature of one sharp, the chart 21 will have its tonic bass on the key of G, and the relative scales, chords, etc., will be shifted to their proper 110 positions with respect to this key signature. By shifting the scale 21 lengthwise, the same particular arrangement will be applicable to each key signature, and regardless of the 115 position of this chart, the various piano keys required to produce the several triads and tetrachords will be plainly indicated, and this without destroying practically the continuity existing between the staff scale and the representation of the keyboard.

From the above, and the disclosure of the drawings, it will be readily understood that I have provided a construction which is complete as to detail and in which the instruction to be given is in a form which enables 120

the result to be obtained in a minimum amount of time, thus especially aiding in providing what may be termed "sight reading."

5 While I have herein shown and described a preferred form in which the invention can be carried into effect, it may be readily understood that changes and modifications therein may be required or desired, and I 10 desire it to be understood that I reserve the right to make any and all such changes or modifications as may be found necessary or desirable in so far as the same will fall within the spirit and scope of the invention as expressed in the appended claim.

15 What is claimed is:

A music chart composed of a bar and a slide thereon, the face of said bar being divided below the slide into spaces of a width 20 to register with the keys of a piano keyboard, said spaces bearing the notes of the diatonic scale, the face of the bar above the

slide bearing a musical staff having the notes of the diatonic scale indicated thereon in registry with the corresponding spaces below, the staff also having registering key names and key signatures and further bearing chord notes; the slide bearing rows of registering spaces arranged to register with the spaces below the slide, the upper row of 25 said spaces bearing brackets and chord names grouping notes into chords, the lower row of the slide spaces bearing numbers indicating the notes of the major diatonic scale, one intermediate row of slide-spaces 30 bearing numbers indicating the notes of the relative minor scale, and a remaining row of slide spaces bearing harmonic indications.

In testimony whereof I affix my signature in presence of two witnesses.

FRANCIS M. WOLFE.
